UNITED STATES PATENT OFFICE.

WILLIAM H. BACH, OF ST. PAUL, MINNESOTA.

DESIGN FOR A BADGE.

SPECIFICATION forming part of Design No. 23,830, dated December 4, 1894.

Application filed April 16, 1894. Serial No. 507,772. Term of patent 7 years.

To all whom it may concern:

Be it known that I, WILLIAM H. BACH, a citizen of the United States, residing at St. Paul, in the county of Ramsey and State of Minnesota, have invented and produced a

new and original Design for a Badge, of which the following is a specification, reference being had to the accompanying drawings, showing the design, in which—

10 Figure 1 is a face view, and Fig. 2 is an edge view of a badge embodying my design.

The leading characteristic features of my design consist of the ornamentation upon and shape of the badge as hereinafter described 15 and as shown in the drawings.

In the center of the badge is the representation of a human face. Surrounding the face is a band, circular in shape and broken by the rays running from the face to the edge 20 of the band, the face and circular band surrounding it representing the dark center of a sunflower. Upon the circumference of the band are twenty four leaves, twelve of them 25 being front leaves and showing their full form each having its point turned toward the

right, and twelve being back leaves showing only the proportion of the leaf that would naturally show when the point was placed midway between the points of the front layer of leaves.

This design is set in a diamond shaped field as shown between the outer edge of the sunflower and the dark lines of the border.

The entire design is surmounted by the border as shown in the accompanying drawings. Upon the inside of this border, surrounding the diamond field and marking its confines is a broken or dotted line; on the outside the border is finished with the scalloped edge while between the dotted lines 35 and scalloped edge are the ornamental lines 40 as shown in the drawings.

What I claim is—

The design for a badge as herein described and shown.

WM. H. BACH.
